UNITED STATES PATENT OFFICE.

HARRY L. WALDRON, OF PROVIDENCE, RHODE ISLAND, ASSIGNOR OF ONE-HALF TO WALTER H. CROWNINSHIELD AND CHARLES H. LAWTON, OF PAWTUCKET, RHODE ISLAND.

COMBINED VIZOR AND EYE-SHIELD.

SPECIFICATION forming part of Letters Patent No. 694,449, dated March 4, 1902.

Application filed November 23, 1901. Serial No. 83,445. (No model.)

To all whom it may concern:

Be it known that I, HARRY L. WALDRON, a citizen of the United States, residing at Providence, in the county of Providence and State of Rhode Island, have invented certain new and useful Improvements in a Combined Vizor and Eye-Shield, of which the following is a specification, reference being had therein to the accompanying drawings.

10 Like letters indicate like parts.

Figure 1 is a front elevation of a cap embodying my invention. Fig. 2 is a view of my said invention, partly in side elevation and partly in section, on line xx of Fig. 3. 15 Fig. 3 is a plan of said invention. Fig. 4 is a view, partly in side elevation and partly in section, on line xx of Fig. 3, showing the eye-shield in its vertical wearing position. Figs. 5 and 6 are detail views.

20 My invention consists of the combination of the vizor of a cap and an eye-shield mounted so as to slide and turn vertically thereon, as hereinafter particularly described, and specifically set forth in the claims.

25 In the drawings, A represents a cap having the vizor B and the lining C, all of the usual construction. The vizor B has the lining D, and both are united on their outer edges by the binding E, stitched thereon, as shown.

30 The eye-shield consists of a frame F, made in the form illustrated in Fig. 3, having at its opposite ends the extensions or ear-pieces G, and also provided with two lens-apertures, each of which is substantially elliptical or oval in shape. Two transparent lenses H H are attached to the frame F by rivets, cement, or in any other suitable manner.

The frame F of the eye-shield is preferably made of vulcanized rubber, but may be made 40 of celluloid, wood, metal, or any proper material. The lenses H H are preferably made of sheets of mica, but may be made of glass, celluloid, or other suitable transparent material.

45 The frame F has the central narrow tapering opening or slot a, the closed inner end of which is preferably concaved and formed in the arc of a circle. The outer edges of the frame F, projecting beyond the lenses and 50 indicated at b b, are curved to correspond to

the curvature of the outer edge of the vizor B when the eye-shield is folded into contact with the vizor, as shown in Fig. 3. The frame F also has its inner edge curved to conform to the inner curvature of the vizor B, as shown 55 in Fig. 3.

On each side of the vizor B it is perforated, and a wire loop M passes therethrough. This wire loop M is made of spring-wire, and it is illustrated on an enlarged scale in Fig. 6. It 60 has the straight stem c, whose outer end is screw-threaded and projects out through the perforation of the vizor B. A nut N engages with the end c, and thus holds the loop M to the vizor B. The portion d of the loop M 65 extends at a right angle with the stem c and lies in contact with the surface of the vizor-lining D. A loop e extends from the straight portion d and is substantially bent circularly for nearly two hundred and seventy degrees. 70 Then the wire is bent to form a substantially straight returning portion f near to and parallel with the straight portion d, already described. The wire loop M terminates in a circular bend g of about ninety degrees, and 75 the end of the wire passes through an aperture (which it exactly fits) in the vizor-lining D and abuts the inner surface of the vizor B, all as illustrated in Fig. 6. The parts d, e, and f have a limited spring movement be- 80 cause of the resilience of the wire of which it is made.

The projecting earpieces G on the ends of the frame F pass, respectively, through the wire loops M and are of a thickness slightly 85 more than the normal distance between the portions d and f of the wire loops M, so that when said projecting earpieces G are between said portions d and f of the wire loop M the said loop is somewhat sprung and said 90 portions thereof are slightly spread apart. Therefore when the eye-shield is in the position shown in Figs. 2 and 3 the earpieces G are held and firmly embraced by the wire loop M, and the eye-shield consequently lies 95 against the vizor-lining D and is secure in said position.

When it is desired to bring the eye-shield into the position shown in Fig. 1, it is slid or moved along by hand from the position shown 100

in Fig. 2 and in Fig. 3 in solid lines to the position shown in Fig. 3 in dotted lines. The earpieces G being then within the enlarged circular bend or loop e are free to move there-
5 in, and the eye-shield by gravity swings to the vertical position shown in Fig. 1 and also in Fig. 4 in solid lines, which is the wearing position, the ear-pieces G then resting upon the bottom of the loop e at the point marked
10 z in Fig. 6.

In Fig. 5 is shown, on an enlarged scale, a fastening device O to aid in maintaining the eye-shield in proper position when not in use. It is made of wire, having the stem m screw-
15 threaded at its outer end, an elongated loop n, extending at a right angle from the stem m, a return bend or loop o, and a bent end p. The stem m passes through a perforation made therefor through the vizor B and vizor-
20 lining D, and a nut P engages with said stem on the outside of the vizor B. The end p ex-
25 tends through an aperture in the vizor-lining D and abuts the inner surface of the vizor B, all as is illustrated in Fig. 5. The reënter-
30 ing of the bent end g of the wire loop M into and through the vizor-lining D serves to pre-
35 vent the wire loop from lateral displacement or circular movement. In like manner the reëntering of the bent end p of the fastener
30 O into and through the vizor-lining D serves to prevent said fastener O from lateral dis-
placement or circular movement. Such re-
sult, however, may be accomplished in other
ways.

35 When the eye-shield is not in use, it is in the position illustrated in Figs. 2 and 3, the central portion of the frame F being snugly held between the loops n and o of the fastener P and the projecting earpieces G of the
40 frame being held and clamped between the portions d and f of the spring-wire loop M. When the eye-shield is drawn forward from the position shown in solid lines in Fig. 3 to the position shown in dotted lines in said fig-
45 ure the inner central portion of the frame is disengaged from the fastening device O, be-
cause it is moved therefrom and the project-
ing earpieces G enter the enlarged loop e and turn, so that the eye-shield hangs vertically
50 downward, as already described.

The spring clamping action of the wire loops M is sufficient to hold the eye-shield in its position in contact with the vizor-lining D, and therefore the central fastening de-
55 vice O may be dispensed with, if desired. I prefer, however, to use said fastening device O, as it insures a more snug fit of the eye-
shield against the vizor-lining D.

60 The wire loops M serve both as guides and hinges to hold and control the movements of the eye-shield, which is mounted thereon. If the eye-shield did not first move in a linear direction, as illustrated in Fig. 3, the eye-
shield would not be clear of the forehead in
65 swinging down, but would be liable to come

in contact with the eyebrows and forehead of the wearer; but if the eye-shield is first moved beyond the eyebrows and forehead and then is swung vertically downward it is then in proper and comfortable wearing position.

70

Caps provided with these adjustable eye-
shields are useful for motormen of electric
cars, locomotive-engineers, drivers of horses
or automobiles, and for other persons who are
engaged in outdoor work and exposed to snow,
75 sleet, or dust while attending to the duties of
their respective employments. When the
weather conditions are favorable and the eye-
shields are not needed, these shields are
snugly turned up and folded against the vizor-
80 lining and are securely held there, where
they are not in the way and are concealed
from view; but as soon as the eyes require
protection from snow, sleet, hail, rain, or dust
the eye-shield can be instantly lowered and
85 brought into the position shown in Fig. 1,
covering the eyes in front, and so affording
the needed protection.

If desired, the lenses may be tinted by a
thin coating of lacquer, or colored lenses may
90 be used to protect the eyes from the strong
glare of sunlight or from the intense white-
ness of snow.

I claim as a novel and useful invention and
desire to secure by Letters Patent—

95

1. In a cap, the combination of a vizor, an
eye-shield having transparent lenses and pro-
vided with two earpieces at its ends, two
spring-wire loops engageable with said two
earpieces of the eye-shield, respectively, each
100 of which loops has a screw-threaded stem
passing through the vizor and comprises a
parallel and resilient guideway and a curved
loop both adapted to direct the proper move-
ment of the eye-shield, and a nut engaging
105 the screw-threaded stem of each spring-wire
loop, substantially as shown.

2. In a cap, the combination of a vizor, a
vizor-lining, an eye-shield having transparent
lenses and provided with two earpieces at its
110 ends, two spring-wire loops engageable with
said two earpieces of the eye-shield, respec-
tively, each of which loops has a screw-thread-
ed stem passing through the vizor and has a
straight portion thereof lying in contact with
115 the under surface of the visor-lining, a curved
open loop, a portion lying parallel with and
adjacent to said straight portion and a bent
free end, which latter passes freely through
an aperture in the vizor-lining and abuts the
120 inner surface of said vizor and a nut engag-
ing the screw-threaded end of each of said
wire loops, substantially as described.

In testimony whereof I affix my signature
in presence of two witnesses.

HARRY L. WALDRON.
